Primary Examiner — Marianne N Pandozzi(74) *Attorney, Agent, or Firm* — HeedLaw Group, PLLC; Thomas P. Heed(57) **CLAIM**

The ornamental design for a tiered fajita server, as shown and described.

DESCRIPTION

FIG. 1 is a perspective front view of the center stack support of the tiered fajita server showing our new design with the rest of server removed for convenience of illustration;

FIG. 2 is a perspective front view of the base serving dish of the tiered fajita server with the rest of the server removed for convenience of illustration;

FIG. 3 is a perspective front view of the middle serving dish of the tiered fajita server with the rest of the server removed for convenience of illustration;

FIG. 4 is a perspective front view of the top serving dish of the tiered fajita server with the rest of the server removed for convenience of illustration;

FIG. 5 is a perspective front view of the entire tiered fajita server; and,

FIG. 6 is a perspective front view of the entire tiered fajita server in an alternate position.

1 Claim, 4 Drawing Sheets(56)
